UNITED STATES PATENT OFFICE.

WILLIAM MASON, OF NEW HAVEN, CONNECTICUT, ASSIGNOR TO THE
WINCHESTER REPEATING ARMS COMPANY, OF SAME PLACE.

MAGAZINE FIRE-ARM.

SPECIFICATION forming part of Letters Patent No. 289,676, dated December 4, 1883.

Application filed September 10, 1883. (No model.)

To all whom it may concern:

Be it known that I, WILLIAM MASON, of New Haven, in the county of New Haven and State of Connecticut, have invented a new Improvement 5 in Magazine Fire-Arms; and I do hereby declare the following, when taken in connection with accompanying drawings and the letters of reference marked thereon, to be a full, clear, and exact description of the same, 10 and which said drawings constitute part of this specification, and represent, in—

Figure 1, a sectional side view showing the parts in their closed or normal position; Fig. 2, a sectional side view showing the parts in 15 their extreme open position; Fig. 3, a sectional side view showing the parts in a partially-opened position, and for illustration of the invention; Figs. 4 and 5, horizontal sections of the receiver, showing top views of the 20 carrier, respectively, in its up and down position; Fig. 6, a vertical section on line *x x* of Fig. 1; Fig. 7, a vertical section on line *y y* of Fig. 1; Fig. 8, a top view of firing-pin and lever, looking down, to illustrate the operation 25 in retracting the firing-pin; Fig. 9, a sectional view at the rear end of the barrel, looking toward the front face of the breech-piece; Fig. 10, the firing-pin detached in perspective; Fig. 11, the ejector detached in perspective.

30 This invention relates to an improvement in that class of magazine fire-arms in which the breech-piece is arranged to move backward and forward in an axial line with the barrel to open and close the breech, the breech-piece operated by means of a lever below, and in which a carrier is hung in the receiver at the rear, so 35 that its forward end, receiving a cartridge from the magazine, is raised as the breech-piece is opened to present the cartridge into a position forward of the breech-piece, and so 40 that the return of the breech-piece will force the cartridge forward from the carrier into its place in the barrel, parts of the invention being applicable to breech-loading fire-arms; 45 and the invention consists in hinging the trigger-guard lever directly to the breech-piece and above the carrier, combined with a link, one end hinged in the receiver below the carrier, the other end hinged to the trigger-guard

lever, whereby that part of the lever above 50 the connection with the link and the link itself form the locking-strut to resist recoil of the breech-piece; also, in a carrier hung at the rear for both longitudinal and up-and-down vibratory movement, whereby the longitudinal 55 movement will permit it to grasp the cartridge received from the magazine, and then by its upward movement present it to a position between the open breech-piece and the barrel, and then return open from its grasping position 60 to receive the next cartridge from the magazine, and in details of construction, as hereinafter described; and more particularly recited in the claims.

A is the receiver, within which the operative mechanism of the arm is arranged; B, the barrel, attached to the forward end of the receiver in the usual manner; C, the magazine, arranged beneath the barrel, both the barrel and the magazine opening at the rear into the 70 receiver in the usual manner, the receiver also constructed for attachment to the stock in the usual manner.

D is the breech-piece, arranged in axial line 65 with the barrel, and so as to be moved in said line from and toward the barrel, as from the position in Fig. 1 to that in Fig. 2 and return, guided in such movement by ribs E on its side, working in corresponding longitudinal 75 grooves, F, in the receiver.

G is the trigger-guard lever, and which also serves as the lever for operating the breech-piece. This lever extends upward through an opening in the bottom of the receiver, and is pivoted to the breech-piece, as at *a*. 80

H is a link, one end hung by a pivot, *b*, to the lever G below its connection with the breech-piece, the other end of the link hung upon a pivot, *d*, transversely through the receiver, and so that when the breech-piece is 90 in the closed position, as seen in Fig. 1, the three pivots *a*, *b*, and *d*, are in line, or nearly so, and whereby the thrust or resistance of the breech-piece is transferred through the upper arm of the lever and link to the pivot *d*. To 95 open the breech-piece, the lever is turned downward in the usual manner of operating this class of levers; but instead of turning

upon its own fixed pivot, as in the usual construction, the link H turns upon the fixed pivot, bringing its pivot b downward as the breech-piece moves backward, until it arrives 5 to the fully-open position, as seen in Fig. 2, the movement of the link H being governed by the movement of the end of the lever attached to the breech-piece, that end moving in a straight line with the breech-piece instead of in the 10 arc of a circle, as that end must do when hung upon a fixed pivot, as in the usual construction. Thus hanging the lever by a link to a fixed pivot permits a firm connection of the lever with the breech-piece, and without the 15 play necessary in the usual construction.

I is the hammer, hung in the usual manner upon its pivot e, and so as to stand with its nose in rear of the breech-piece when the breech-piece is in its closed position; hence when the 20 breech-piece is opened, as before described, the hammer is thrown backward to the position of full-cock, and when it has arrived at the position of full-cock the breech-piece escapes from and passes over the hammer, as 25 seen in Fig. 2, the breech-piece having a longitudinal groove or recess, L, upon its under side to permit it thus to pass over.

M is the firing-pin, arranged longitudinally through the breech-piece, and guided therein 30 for longitudinal movement, its forward end or nose, f, projecting, under the pressure of the hammer, forward of the front face of the breech-piece, as seen in Fig. 1, so as to strike the primer in the head of the cartridge. Near the 35 forward end of the firing-pin is a shoulder, h, which lies in a recess, i, in the forward end of the lever G. This recess i forms a shoulder, l, as seen in Fig. 8. When the parts are in their normal condition, as seen in Fig. 1, this 40 shoulder on the lever is so far forward that the firing-pin may reach its extreme forward position; but as the lever G is turned in opening the breech-piece, the cam-like shoulder l on the lever engages the shoulder h on the firing-pin and retracts that pin, as seen in Fig. 45 2. To engage the firing-pin in this retracted position, so that when the breech-piece is moved forward the nose of the firing-pin cannot come into contact with the primer until 50 all the parts are in the proper condition for firing, a latch, K, is hung in the breech-piece upon a pivot, m, and below a recess, n, in the firing-pin, and so that as the breech-piece reaches its extreme rear position, as seen in Fig. 2, the latch K comes in contact with the nose of the 55 hammer I, and so as to turn the nose of the latch up into a position in front of the rear end of the slot n in the firing-pin, and thus lock the firing-pin in its withdrawn or retracted 60 position. Then when the breech-piece is thrown forward to the position seen in Fig. 1, a shoulder, r, above the pivot b of the lever G strikes an arm, s, on the latch forward of its pivot, and so as to turn the nose of the latch 65 down out of engagement with the firing-pin, and so that the firing-pin may be forced for-

ward by the hammer, as seen in Fig. 1. On the upper side of the breech-piece the extractor N is fitted, and secured by a pin, t, transversely through the breech-piece and extractor. The forward end, u, projects and is of the usual hook shape, so as to engage the flange of the cartridge, the elasticity of the extractor permitting it to ride over the flange on the cartridge as the breech-piece is brought to its closed position. An arm, w, extends from the extractor to the rear, and so as to bear upon a cam-like projection, 2, on the latch K, as seen in Fig. 1. The arm w is also elastic, and serves as a spring to act upon 80 the latch K, and so that when the latch is thrown up into engagement with the firing-pin, as seen in Fig. 2, the arm w of the extractor bears upon the projection 2, serving to hold it in its engaged position until, in the 85 forward movement of the breech-piece, the latch is returned into the position seen in Fig. 1, as before described. Thus the extractor-piece serves the double purpose of extractor and a spring for the latch K, and as the arm w is 90 thrown upward on closing the breech-piece it adds an increased power to the extractor, serving to more firmly engage the extractor with the flange of the cartridge than the extractor would do of its own individual elasticity, and then when the breech-piece is opened, as seen in Fig. 2, and the arm w depressed, the additional power of the extractor is relaxed to facilitate the ejection of the cartridge.

P is the ejector, arranged in the breech-piece 100 parallel with the firing-pin, its forward end substantially surrounding the firing-pin, as seen in Fig. 9. The rear end of the ejector, when the parts are in their normal condition, as seen in Fig. 1, stands forward of the cam-like projection 2 on the latch K, and as the breech-piece is thrown backward it retains substantially the same relation to the latch until the breech-piece approaches its rear position, as seen in Fig. 3, the normal position of the forward 105 end of the extractor being flush with the front face of the breech-piece, as seen in Figs. 1 and 3. In completing the rear movement of the breech-piece, and as the latch is turned into its position of locking the firing-pin, as seen in Fig. 110 2, the projection 2 on the latch strikes the rear end of the ejector and forces it forward to drive its forward end out beyond the front face of the breech-piece, as seen in Fig. 2, and which movement of the ejector is imparted to 115 the cartridge-shell to throw it from its engagement with the breech-piece. Then as the latch is turned, as before described, the ejector recedes into its normal position, as seen in Fig. 1.

R is the carrier. Its rear end is constructed 125 with a slot, 3, and through which slot the pivot e passes to serve as a pivot for the turning of the breech-piece. The slot 3 permits a certain amount of forward-and-back movement of the carrier. The arm of the lever G extends 130 up through an opening, 4, in the carrier. The forward end of the carrier is divided longitu-

dinarily and vertically, so as to permit its contraction and expansion, as from the position seen in Fig. 4 to that seen in Fig. 5. The two parts 5 5 of the forward end of the carrier are recessed upon their inner faces, as seen in Figs. 4, 5, and 6, corresponding, substantially, to more than half the circumference of the cartridge-shell. The sides of the carrier from the hub forward are elastic, so as to permit them to be contracted or expanded, as before described, the expansion being automatic and produced by the elasticity of the sides. On the outer side of the two parts of the carrier is a projection, 6, and upon the inner sides of 5 the receiver is a recess, 7, in which these projections stand when in their normal position, as seen in Fig. 1. The rear edge of these recesses is inclined backward, as seen in Figs. 4 and 5, and the rear edge of the projection 6 should be also inclined, as seen in Figs. 4 and 5. The upper part of the lever G, as before described, works through the carrier between its two sides. As the lever approaches its extreme rear position, as seen in Fig. 3, the lever strikes a shoulder, 8, on the carrier above its pivot e. The first effect of thus striking the shoulder 8 is to give to the carrier a rear movement and bring it into the position seen in Fig. 3, the slot 3 permitting such rear movement. In 30 such rear movement the projections 6 on the outer sides of the carrier ride from the recesses 7 in the receiver onto the inner surface of the receiver, as from the position seen in Fig. 4 to that seen in Fig. 5, which causes the two parts 35 5 of the forward end of the carrier to approach each other, as seen in Fig. 5. Thus when the forward end of the slot 3 is brought into contact with its pivot e, the final movement of the lever G from the position seen in Fig. 3 to that seen in Fig. 2 will turn the carrier up 40 from the position seen in Fig. 3 to that seen in Fig. 2, the projections 6 riding upon the inner surface of the receiver, so as to be retained in their contracted position. Then when 45 the breech-piece is returned, as before described, the forward edge of the lever strikes a shoulder, 9, on the carrier, the first action of which is to force the carrier forward, as seen in broken lines, Fig. 2, until the projections 6 enter an upward extension, 10, from the recess 7 in the carrier, which permits the two sides of the carrier to separate, as seen in Fig. 4, and then the continued movement of the lever forces the carrier into its down position, 50 as seen in Fig. 1, and leaves it in its open position, as seen in Figs. 4 and 6.

The operation of the arm is as follows: The parts standing in the normal position, as seen in Fig. 1, the magazine charged in the usual manner, may be through an opening, 11, on the right-hand side or otherwise, the rear cartridge stands with its head against the downward projection 12, on the breech-piece, as seen in broken lines. Then, as the breech-piece 55 is opened, the rear cartridge in the magazine follows the breech-piece in its rear movement

until it arrives at its proper position on the carrier, as seen in Fig. 3. Then the continued movement of the lever G and breech-piece, as before described, raises the carrier, and presents the cartridge in its position between the front face of the breech-piece and the rear end of the barrel, as seen in broken lines, Fig. 2. The first rear movement of the carrier closes 75 the two sides of the carrier upon the cartridge, so as to prevent the cartridge being thrown out of position by the quick ascent of the carrier, but yet so as to permit the cartridge to be forced forward through the carrier. Then as the carrier is forced forward it opens, so as 80 to permit it to drop and escape from its cartridge in its descent. Then, as the breech-piece completes its closing movement, the extractor engages the flange of the cartridge, and so that, either before or after firing, when the breech-piece is again withdrawn the discharged shell or cartridge, as the case may be, will be withdrawn, with the breech-piece held by the extractor against the shoulder 13 below, until the ejector comes in contact with the projection 2 on the latch, as before described. Then the continued rear movement of the breech-piece gives, substantially, a quick forward movement to the ejector into the position seen in Fig. 2, which will force the shell forward, the upper end of the flange held by the extractor, so that the forward end will be turned up, the quick movement of the ejector serving to throw it up through the opening in the receiver in the usual manner for ejecting 100 cartridge-shells.

I have represented the hammer as serving to turn the latch K up into its position of locking the firing-pin; but it will be readily seen that any obstruction in the path of the latch 105 will turn it into that locking position. This arrangement of latch for locking the firing-pin may be employed with other mechanisms for operating the breech-piece.

The breech-piece and its operative mechanism may be employed with other vibrating carriers—that is, the carrier may be hung upon the pivot without longitudinal movement, or without the grasping effect upon the cartridge.

While the recess 10, to permit the opening 110 of the carrier, is desirable, it may be omitted, the closing of the carrier by the passage of the projection 6 from the recesses being only to an extent that will produce sufficient friction upon the cartridge to prevent its being thrown upward as the carrier rises. Then, as the carrier descends, the projections will enter the recesses 7, and there expand for the free passage of the next cartridge from the magazine 120 onto the carrier.

Instead of making the recesses in the receiver and the projections on the carrier, it will be readily seen that this order may be reversed—that is, the recesses formed in the carrier, and projections in the receiver. I wish 130 to be understood, therefore, as embracing this reversed order of construction as an equiva-

lent for that hereinbefore described and hereinafter claimed.

While I prefer to operate the carrier by means of the lever, as described, the downward projection 12 from the breech-piece may operate between the shoulders 8 and 9, substantially as does the lever, it only being necessary in so doing that the shoulder shall be arranged at a proper relative position to said downward projection, and this would be desirable in arms in which, for illustration, the breech-piece were moved by a handle, instead of by a lever, from beneath.

I am aware that fire-arms have been constructed with the trigger guard lever hinged to the breech-piece, and with a link connected to the lever and to the receiver, whereby the turning down of the lever will draw back the breech-piece, the upper end of the lever following the breech-piece; but in such constructions the link performs no other office than that of aiding in the opening and closing movement of the breech-piece. It in no way sustains the breech-piece against recoil, the lever only performing this office and independent of the link-connection, whereas in my invention the link and lever are hung in such relation to each other and to the breech-piece that they together form the strut to support the breech-piece against recoil.

I claim—

1. In a magazine fire-arm, the combination of a carrier, the breech-piece arranged to move longitudinally in the receiver, the trigger-guard lever G, its upper end hung to the breech-piece above the carrier, and the link H, its one end hung upon a pivot in a receiver below the carrier, its other end hinged to the lever G, substantially as described, and whereby said lever and link form a strut for the support of the breech-piece from a point above the carrier to a point below the carrier, substantially as described.

2. In a fire-arm, the combination of a longitudinally guided and movable breech-piece, the firing-pin arranged longitudinally in said breech-piece, mechanism, substantially such as described, to impart to said breech-piece longitudinal movement and to the firing-pin a rear or retracting movement, and a latch, K, hung in said breech-piece independent of the mechanism which imparts the said longitudinal and retracting movement, and arranged to engage said firing-pin in its retracted position and release it as the breech-piece is closed, substantially as described.

3. In a fire-arm, the combination of a longitudinally - movable breech - piece, the firing-pin arranged longitudinally through said breech-piece, mechanism, substantially such as described, for imparting to said breech-piece longitudinal movement and to said firing-pin a rear or retracting movement, the latch K, hung in said breech-piece, and the extractor N, having an arm, w, extending therefrom, and arranged to serve as a spring upon said latch, substantially as described.

4. In a fire-arm, the combination of a longitudinally-movable breech-piece, a firing-pin arranged longitudinally through said breech-piece, mechanism, substantially such as described, for imparting longitudinal movement to said breech-piece and retracting movement to said firing-pin, the ejector P, also arranged longitudinally in said breech-piece, and the latch K, hung in said breech-piece, and arranged to engage the firing-pin in its retracted position and to force said ejector forward as the breech-piece completes its rear movement, substantially as described.

5. In a magazine fire-arm, the combination of a longitudinally-movable breech-piece, and mechanism, substantially such as described, for imparting thereto a longitudinal movement, the carrier hung at the rear to permit both longitudinal and vibratory movement of the carrier, mechanism, substantially such as described, for imparting longitudinal and vibratory movement to the carrier, the carrier divided vertically at its forward end, its two sides elastic, each side carrying an outward projection, 6, and the receiver constructed with a recess, 7, whereby the rear longitudinal movement imparted to the carrier will cause the two sides of the carrier to approach each other before it commences its ascent, substantially as described.

6. In a magazine fire-arm, the combination of a longitudinally-movable breech-piece, and mechanism, substantially such as described, for imparting longitudinal movement thereto, a carrier hung at the rear to permit both longitudinal and vibratory movement, mechanism, substantially such as described, to impart both longitudinal and vibratory movement thereto, the carrier divided vertically at its forward end, its two sides elastic, each side carrying an outward projection, 6, the receiver constructed with a recess, 7, whereby the rear longitudinal movement imparted to the carrier will cause the two sides of the carrier to approach each other before it commences its ascent, and a recess, 10, in connection with said recess 7, and into which recess 10 the forward movement of the carrier will bring the projection 6 before the carrier commences its descent, substantially as described.

7. The combination of a longitudinally movable and guided breech-piece, D, the lever G, its upper end hung to the breech-piece, the link H, one end hung upon a pivot in the receiver, the other end hung to said lever, a carrier, R, hung upon a pivot in rear of said lever, the said lever extending upward through said carrier, and the carrier constructed with a shoulder, 8, at the rear of the lever, and shoulder 9 forward of the lever, whereby the opening movement of the lever will raise the carrier and the forward movement depress it, substantially as described.

8. The combination of the longitudinally-movable breech-piece D, the lever G, its upper end hung to the breech-piece, the link H,

one end hung upon a pivot in the receiver, the other end hung to the lever, the carrier R, constructed with a longitudinal slot, 3, at its rear, through which its pivot passes, and 5 divided vertically at its forward end, its two sides elastic, and also constructed with a shoulder, 8, in rear of and a shoulder, 9, forward of said lever, and with an outward projection, 6,

upon its sides, and the recess 7 in the sides of the receiver, with an extension, 10, therefrom, substantially as described. 10

WILLIAM MASON.
